SUPPORTING DEVICE FOR STRANDED TRANSMISSION LINE CONDUCTORS

Miles O. Bolser, Los Angeles, Calif.

Application January 19, 1934, Serial No. 707,366

6 Claims. (Cl. 248—31)

This invention relates to a supporting device for stranded transmission line conductors. It is especially adapted to support large hollow core conductors of the segment type. Type HH of 5 the General Corporation is an example. The segments or strands of relatively heavy electrical conductors are twisted or spiralled about the axis of the conductor so that the conductor can be bent and follow the various necessary directions without bringing undue stresses of either compression or tension, upon the same.

Broadly speaking, the primary purpose of the present invention is to provide a supporting device for cables of the character indicated, so 15 constructed that while the cable can not run therethrough if the cable should break yet the engagement of the said device with the cable is such as to permit freedom of movement of the cable with respect to the supporting device, 20 under the conditions of use and in such manner as to prevent objectionable stresses which have been inherent in the clamps or supports heretofore commonly employed.

Further objects and advantages of the invention 25 will be set forth in the detailed description which follows.

In the accompanying drawing,

Figure 1 is a plan view and Figure 2 is a side 30 elevation of a clamp constructed in accordance with the invention.

Figure 3 is a transverse sectional view upon line 3—3 of Figure 2.

Figure 4 is a transverse central sectional view 35 and

Figures 5 and 6 are diagrammatic views hereinafter described.

Like numerals designate corresponding parts 40 in all the figures of the drawing.

The supporting device of the present invention

45 comprises an elongated shell 5 of general U-shape in cross section. This shell may be supported in any desired manner, as for example, by means of the hanger 6 and trunnions 7; said trunnions being engaged in thickened portions 8 of the shell.

The material of the shell may be thickened 50 adjacent its opposite ends to provide the hub-like portions 9 which constitute bearings for the trunnions 10 of transverse saddles 11. The cable is indicated at 12, and an inspection of Figure 3 will show that these saddles merely support the cable but are not clamped or gripped thereto.

At the central portion of the support a two-part grip is secured upon the cable; this grip 55 comprising an upper element 13 and a lower element 14; these elements being adapted to be

gripped on the cable by means of the screws 15. This grip carries studs 16 which enter vertical slots 17 formed in the thickened portions 8 of the shell. This arrangement floatingly mounts the cable with respect to the shell while preventing endwise movement of the cable through the shell. The cable may yield freely in all necessary ways while at the same time the studs 16 will prevent endwise movement of the cable through the clamp if a cable should break.

I am aware of the fact that known cable hangers or supports are constructed to support a cable at a plurality of points. However, it has been found that where the cable is positively gripped at a plurality of points, highly objectionable 60 strains and stresses result. This is especially true where the points of gripping are less than one lay of the cable apart. Calculations upon a type HH cable to be used on the Boulder Canyon transmission line and supported by a known 65 type of clamp positively gripping the cable show that when said cable is subjected to a vibration angle at the supports of 2°, a stress of 27,000# per square inch is induced in the top and bottom 70 segments of the cable. Measurements of these 75 segment stresses, by means of an extensometer, have shown them to be detrimental to the life of the cable in service.

In the bending of a stranded cable or conductor, the least stress is induced in the segments 80 when the bend involves uniformly one lay of the conductor or a multiple number of lays.

The individual strands or segments of the conductor acting as rigid elements have stresses induced in them as a result of bending, and under 85 any given bend these stresses are the least when the bend is uniformly distributed over the greatest possible length of conductor.

Tests have shown that when the two supporting 90 saddles 11 are $\frac{1}{4}$ lay from the center of the structure, or a distance of $\frac{1}{2}$ of the lay of conductor between saddles, the radius of curvature is almost exactly the theoretical radius of curvature for a circle involving one lay of cable, and this gives almost perfect results, from the stand-point of preventing the setting up of objectionable 95 strains and stresses in the cable.

Therefore, while I do not wish to limit myself to any particular distance between the saddles, and while the use of these saddles having free 100 engagement with the cable is to be covered broadly and irrespective of the distance between them, yet, I wish, as a subsidiary feature to lay stress on the fact that if these saddles be disposed as described, i. e., a distance equal to $\frac{1}{2}$ lay of con- 105

110

ductor, highly advantageous results may be secured.

Further, I find it desirable to make the longitudinal radius of the supporting surface of the 5 saddles equal to 2½ times lay of conductor.

In Figure 5 I have illustrated the result of vibration out of phase upon opposite sides of the clamp or support this figure showing that under those conditions there is relative bending between 10 the conductor and the clamp.

In Figure 6 I have diagrammatically illustrated that vibration in phase on opposite sides of the clamp induces no relative bending between conductor and clamp.

15 Having described the invention, what I claim is:

1. A supporting device for conductors or cables consisting of supporting members pivoted to a shell or body in which are pivoted, at either end, 20 a supporting saddle that does not grip or clamp the conductor; a clamp or grip for the conductor located between the two saddles, free to float with the conductor in the vertical direction but restricted from moving in the longitudinal direction.

2. A supporting device for conductors or cables consisting of supporting members pivoted to a shell or body in which are pivoted, at either end, a supporting saddle that does not grip or clamp 30 the conductor; a double cone type clamp or grip for the conductor located between the two saddles, free to float with the conductor in the vertical direction but restricted from moving in the longitudinal direction.

35. 3. A supporting device for conductors or cables consisting of supporting members pivoted to a

rigid shell or body in which are pivoted, at either end, a supporting saddle that does not grip or clamp the conductor; a clamp or grip for the conductor located between the two saddles, free to float with the conductor in the vertical direction but restricted from moving in the longitudinal direction; a curved non-angular rigid shell or body that encloses the saddles and clamp all except for a slot on the top and ends sufficient only for the assembly of the device on the conductor, thus reducing corona loss.

80
85

4. A supporting device for conductors or cables consisting of supporting members pivoted to a shell or body in which are pivoted, at either end and at one half segment or strand lay of the conductor apart, a supporting saddle that does not grip or clamp the conductor; a clamp or grip for the conductor located between the two saddles, free to float with the conductor in the vertical direction but restricted from moving in the longitudinal direction.

90
95

5. A device of the character described comprising an elongated shell, a hanger supporting said shell at substantially its central point, a transverse saddle trunnioned in the shell adjacent each 100 of its ends, said saddles being constructed to support but not to grip a cable, a grip adapted to be gripped upon the cable adjacent the central portion of the body, and studs carried by said grip and engaging vertically elongated openings in said shell.

100
105

6. A structure as recited in claim 1 wherein the supporting surfaces of the said saddles are below the supporting surfaces of the trunnions by which said saddles are carried.
